UNITED STATES PATENT OFFICE.

JOSEPH MARIE TERME AND JULES DÉHARBE, OF PARIS, FRANCE, ASSIGNORS
TO THE SOCIÉTÉ ANONYME CO-OPÉRATIVE POUR LA CONSTRUCTION DE
CHAUDIERES INEXPLOSIBLES, OF SAME PLACE.

MULTITUBULAR BOILER.

SPECIFICATION forming part of Letters Patent No. 372,580, dated November 1, 1887.

Application filed February 15, 1887. Serial No. 227,755. (No model.) Patented in France September 3, 1885, No. 170,991; in England April 13, 1886, No. 5,132, and in Germany April 21, 1886, No. 37,788.

To all whom it may concern:

Be it known that we, JOSEPH MARIE TERME and JULES DÉHARBE, citizens of the Republic of France, residing at Paris, in said Republic, have 5 invented certain new and useful Improvements in Multitubular Boilers, (for which we have obtained patents in France September 3, 1885, No. 170,991; in England, April 13, 1886, No. 5,132, and in Germany April 21, 1886, No. 10 37,788,) fully described and illustrated in the following specification and the accompanying drawings, forming part of the same.

This invention has reference to multitubular boilers in which the water to be evaporated is 15 caused to travel through a series of inclined tubes while such tubes are acted upon externally by the flame and products of combustion from the furnace.

The improvements mainly consist, first, in 20 constructing the boiler of a set or sets of groups of three tubes which are free to dilate, one of these tubes leading in an upwardly-inclined direction from a vertical water-head or manifold at the back of the boiler and conveying the 25 water to a water-compartment at the front, while the other two tubes lead also in an upwardly-inclined direction from the water-compartment to the header or manifold at the rear; secondly, in constructing the lowest water- 30 compartments to receive two tubes and in combining them with the lower supply pipe or chamber; thirdly, in the general combination of the groups or tubes, thus arranged and forming a number of sets, with a lower supply pipe 35 or chamber with an upper or main steam-drum, a steam-reservoir, a steam-drier, and a box or pipe for the collection and discharge of sediment.

We will proceed to describe, with the aid 40 of the annexed drawings, the construction of a boiler in which the improvements are embodied.

Figure 1 is a front view of the boiler with its furnace. The set of groups of tubes to the 45 left hand is seen in end view and the next set in section. The other sets are concealed by the door Q. Fig. 2 is a longitudinal section. Fig. 3 is an elevation of the rear end. Fig. 4 is a longitudinal elevation. Fig. 5 is a longi-

tudinal section of a modification, which differs 50 from that represented in the preceding figures in that there are return flame-tubes within the water-tubes. Figs. 6 to 12 are detail views, hereinafter described.

Referring first to Figs. 1 to 4, A is a chamber forming a steam and water reservoir, at the upper part of which is an inlet for steam from the upper or main steam-drum, K, and an outlet, from which steam passes through the pipe L to the drier M. From the lower part of the 60 reservoir A a pipe, B, conveys water therefrom to a supply pipe or chamber, D, below the water-tubes. The feed-water is thus conveyed to this chamber—that is to say, if the water be supplied to the reservoir A and not 65 directly to the pipe D. Below the pipe B is a box or pipe, C, fitted with a discharge-cock for collecting and discharging sediment. At the front of the boiler are water-chambers E 70 G G, superposed in vertical sets, and at the back of the boiler are vertical water headers or manifolds J J, equal in number to the sets of water-chambers; or there may be one common header. The lowest water-chamber, E, of each set is in communication with the supply-chamber D, and is connected by two upwardly-inclined tubes, F F, with the header J at the back of the boiler. The other water-chambers, G G, (which are of approximately V form, so as to rest upon one another, as seen in Fig. 8c 1,) each communicate with the headers by three inclined tubes, of which two, I I, rise from the water-chamber to the header, while the other, H, rises from the header to a higher water-chamber. These three tubes constitute a group 85 or complete element. The feed-water flows from the pipe or chamber D through the tubes F to the headers J, and the headers serve to feed the several groups or elements. The tube H of each group conveys water from the header 90 to the water-chamber G, which distributes it to the tubes I I. The steam formed in the tubes H and I follows the same course as the water, and readily discharges at the ends of the tubes I into the headers J. Above the headers J is 95 the main drum K, which conducts the steam to the reservoir A, from which reservoir the pipe L conveys the steam to the drier M.

From this drier the steam-supply for the engine or other purpose is taken through the valve N. Each water-chamber and each vertical header has at its outer face as many openings as there are tubes communicating therewith, and these openings are fitted with covers P, which can be removed by first releasing the nuts O of the anchor-bolts when it is required to clean the tubes. At the front of the boiler are corrugated or undulating sheet-iron doors Q, to inclose the water-chambers.

R R represent the furnace and its doors, and S S the ash-pit and its doors. When internal flame-tubes are used, (see T T, Fig. 5,) they are fitted within the tubes that rise from the water-chambers to the headers, and they extend at their front end through the water-chamber and at their back end through the headers. The flames, after having acted upon the outside of the sets of tubes, return to the front of the boiler, enter the flame-tubes, and pass out at the back end thereof to the chimney. Each of the water-tubes is formed at the ends with holes to receive the arms or flukes of an anchor-bolt, and this when in place is tightened up by a nut, so as to draw the external cone or taper of the tube end against a corresponding cone of the aperture in which the tube fits, and thereby makes a dry metallic joint. This is represented on a larger scale in Figs. 6, 7, and 8. In these figures A represents the water-tube. a a are the holes therein. C is the anchor-bolt, whose arms or flukes enter the holes a a. B is the header, in which the end of the tube A is mounted. The orifice b is tapered, and the end of the tube A is likewise tapered. D is a cover to the opening in the outer face of the header B, and E is a nut for locking the anchor-bolt C.

Instead of the tube ends being tapered, they may be formed with a ring or boss, b, Fig. 9, or e, Fig. 11, or h, Fig. 12, to make joint with the cone of the aperture in which the tube fits. This ring or boss may be in a piece with the

tube, or be a ring of copper or brass let into it, as represented at d, Fig. 10.

The constructions shown in Figs. 6 to 12, and described above, form no part of our present invention.

What we claim, and desire to secure by Letters Patent, is—

1. In a multitubular boiler, a set or sets of tubes composed of groups of three, in combination with a vertical water-header at one end and with water-chambers at the other end, one tube of each group rising from the header to a water-chamber, and the other two tubes of the group rising from a water-chamber to the vertical header, substantially as set forth and shown.

2. In a multitubular boiler, a bottom water-chamber, E, arranged to receive only two tubes, F F, in combination with a lower water-supply pipe or chamber, D, and with a set or sets of tubes composed of groups of three, having a vertical header at one end and water-chambers at the other end, one tube of each group of three rising from the vertical chamber to a water-chamber, and the other two tubes of the group rising from a water-chamber to the vertical header, substantially as set forth and shown.

3. In a multitubular boiler, the combination of the following parts or elements—viz: a set or sets of tubes composed of groups of three, H I I, water-headers J, water-chambers G, lower water-supply pipe or chamber, D, main steam-drum K, steam-reservoir A, steam-drier M, and sediment pipe or box C, substantially as described and shown.

In testimony whereof we have signed our names to this specification before two subscribing witnesses.

JOSEPH MARIE TERME.
JULES DÉHARBE.
